UNITED STATES PATENT OFFICE.

GEORGE G. GREENBURG, OF CHICAGO, ILLINOIS.

DESIGN FOR A MEDAL.

SPECIFICATION forming part of Design No. 29,528, dated October 25, 1898.

Application filed October 3, 1898. Serial No. 692,563. Term of patent 31 years.

To all whom it may concern:

Be it known that I, GEORGE G. GREENBURG, a citizen of the United States, residing at Chicago, in the county of Cook and State of Illinois, have invented and produced a new and original Design for Medals, of which the following is a specification, reference being had to the accompanying drawings, forming part thereof.

10 In the drawings, Figure 1 is a view in side elevation of a medal embodying my new design. Fig. 2 is a view in elevation of the reverse side thereof. Fig. 3 is a view in central vertical section.

15 As shown in the drawings, the leading or material feature of my design consists of the face having a colonnade with three figures, representing allegorically "Columbia," "Liberty," and "Peace," surmounted upon the 20 entablature of the colonnade, as shown in Fig.

1. A panel for a suitable inscription is mounted upon the entablature of the colonnade. In Fig. 2 of the drawings there is shown the reverse side of the medal, upon which there is a representation of a dove holding a branch of olive in its bill. All the ornamental figures are shown slightly raised from the plain faces of the medal, as seen in Fig. 3. At its edge the medal is formed with a circumferential bead or rib. 25

Having described my invention, what I claim as new, and desire to secure by Letters Patent, is—

The design for a medal, as herein shown and described.

GEORGE G. GREENBURG.
